UNITED STATES PATENT OFFICE.

EDGAR H. FREEMAN, OF TRENTON, NEW JERSEY, ASSIGNOR, BY MESNE ASSIGNMENTS, TO CIRCLE F. MFG. CO., OF TRENTON, NEW JERSEY, A CORPORATION OF NEW JERSEY.

PUSH-SWITCH SOCKET.

Application filed June 9, 1923. Serial No. 644,430.

This invention relates to electric lamp sockets of the so-called push button type having a novel and reliable push-switch construction.

5 A primary object of the invention is to provide a switch mechanism wherein the switch parts are sufficiently large and heavy adequately to carry currents of large capacity, for example 250 watts, and which will 10 also effect a quick make and break.

In the use of lamp sockets in connection with electrical appliances such as washing machines, heaters, irons, stoves and the like, it is necessary to provide a switch mechanism which is sturdy enough to carry the 15 large current required for such devices and which will open and close the circuit quickly to prevent the formation of an arc. In using the ordinary switch mechanism in connection with devices consuming large quantities of current considerable fire risk is involved and in order to meet underwriter's requirements it is necessary to provide a 20 socket that will stand up under extraordinary load conditions and also effect a rapid make and break.

A further object of the invention is to provide a simple, practical and reliable switch mechanism which is capable of facile 25 assembly and is simple and reliable in its operation. In that connection it may be pointed out that the invention contemplates mounting the switch lever in a novel way in the insulating block as well as providing a 30 novel actuating means therefor.

With the above and other objects in view which will more readily appear as the nature of the invention is better understood, the same consists in the novel combination 35

40 and arrangement of parts hereinafter more fully described, illustrated and claimed.

A preferred and practical embodiment of the invention is shown in the accompanying drawings in which—

45 Figure 1 is a vertical longitudinal sectional view of the improved socket.

Figure 2 is also a vertical longitudinal sectional view taken at right angles to Figure 1.

50 Figure 3 is a detail cross sectional view taken on the line 3—3 of Figure 1.

Figure 4 is a sectional view taken on the line 4—4 of Figure 1 looking in the direction of the arrows.

Figure 5 is a detail sectional view taken on the line 5—5 of Figure 3.

Figure 6 is a detail sectional view taken on the line 6—6 of Figure 1.

Similar reference characters designate corresponding parts throughout the several figures of the drawings.

In carrying the invention into effect it is proposed to provide a pair of porcelain or other insulating blocks A and B adapted to be held together, when the socket is assembled by the non-current carrying screws *a* and *b*. The cap block A has a cavity or chamber 1 forming a part of the switch chamber and the base block B is provided on its inner face with a guideway 2 terminating at opposite ends in the enlarged portions 3 and formed with the abutment shoulders 4, the purpose of which will herein-after more fully appear.

The outer face of the base block is formed with an offset portion 5 for facilitating the positioning of the screw shell 6, and is also provided at its central portion with a relatively shallow recess 7 and the bearing seats 8. The portion of the button between the bearing seats is provided with a flaring opening as shown in Figure 5 thereby providing the opposite inclined switch blade abutment walls 9.

Also as shown in Figure 4 the opposite sides of the block B are provided with the recesses 10 and 11 for receiving the line wire binding terminals 12 and 13. The binding terminal 12 is electrically connected through the washer plate *w* with the screw shell contact 6, and the binding terminal 13 is connected with the spring contact finger 14 by screw 14^a.

Another spring contact finger 15 is housed within the switch chamber formed by the complementary parts of the blocks A and B, and this contact finger is electrically connected with the center plug contact 16 of the socket by means of a rivet 17.

Referring more particularly to the switch proper it will be observed that the same comprises an oscillating switch frame C, a shifter member D and an actuator E.

The said switch frame C consists of a substantially U-shaped body 18 and has openings in the ends of its arms to receive a pivot pin 19 adapted to rest in the bearing seats 8 of the base block B, whereby the shifter

member designated generally as D may serve to perform the double function of holding the frame C to its seat and also holding said frame and its actuator E in operative relation.

The said shifter member D consists of the stem or plunger 20 slidably guided in the web 21 of the frame C and has a forked end portion 22, together with a spring 23 mounted on the stem and confined between the said forked portion 22 and the web 21 of the switch member. The notch or recess in the forked portion 22 receives the cross piece 24 of the slide bar 25 of the actuator E, said bar being shiftably mounted on the bottom of the guideway 2 and provided with angularly offset end portions for carrying the push buttons 26 and 27 which move into and out of the enlarged ends 3 of the guideway 20 when manipulated by finger pressure thereby to cause bar 25 to be shifted transversely of the body blocks A and B for operating the switch frame.

As will be observed from Figure 4 the 25 said push buttons 26 and 27 may be limited in their inward movement by the shoulders 4, thereby preventing over-travel of the actuator E. Also, in connection with the said actuator E comprising the slide bar 25 and 30 push buttons 26 and 27 it will be observed that the bar is yieldingly held against the bottom of the guideway 2 by the forked end 22 of the shifter member D, thereby providing 35 a simple and practical mounting for the actuator. In other words the spring 21 exerting its force on the switch frame and the slide bar serves to hold both of these parts in place. To assist in assembling the socket 40 during manufacture, and also insulate the frame and center plug, it is proposed to use a fibre cover piece which is secured in position by the eyelet 17 which connects the contact finger 15 and the center plug contact 16.

When the device is in use it will be apparent 45 that upon shifting or pushing inward of the button 27 the bar 25 will be slidably moved along the guideway 2 and the cross piece 24 thereof will cause the movement of the stem 20 through the opening in the web 20 of the switch frame thereby compressing the spring 23 and storing up energy. As soon as the cross piece 24 passes dead center, that is, the point at which the axis of the stem and the axis of the opening in the web 20 coincide, the switch frame 18 will be snapped 50 automatically into the dotted line position shown in Figure 1 thereby engaging the contact fingers 14 and 15. When the circuit is to be opened the reverse of the above operation 55 takes place and the switch frame 18 is moved back to the full line position shown in Figure 1 with a sharp quick movement, thereby preventing the formation of an arc 60 between the switch frame and the contact fingers when the circuit is opened.

When the switch frame is actuated under the influence of the spring 23 of the shifter member D, the side edges thereof will engage with the inclined walls 9 in the porcelain block B. Thus, the arc of movement 70 of the switch frame 18 is limited by the inclined walls 9 in the block, and likewise the movement of the actuator including the push buttons 26 and 27 is limited by the said push buttons engaging with the shoulders 4 in 75 the insulating body.

From the foregoing it will be apparent that one of the novel and distinctive features of the present invention is the arrangement of the switch frame 18 and the slide 80 bar 25 of the actuator E. The switch frame 18 operates at the side of the block opposite to that in which it is pivoted and the result of this arrangement is that it permits the spring 23 of the shifter member D to perform the dual function of holding the switch frame and slide bar of the actuator member 85 in place.

Without further description it is thought that the features and advantages of the present improvement will be readily apparent to those skilled in the art and it will of course be understood that changes in the form, proportion and minor details of construction may be resorted to without departing from 95 the spirit of the invention or scope of the appended claims.

I claim:

1. A push button socket including a base 100 formed at one face thereof with pivot bearing seats, a shifter member adapted to slidably engage with the other face of the base, a switch member, a pivot pin engaging said switch member and resting in the bearing seats, a plunger engaging the switch member and also engaging the shifter member, and a spring confined between a part of the plunger and switch member and holding the shifter member and the switch member to opposite sides of the base.

2. A socket of the class described including an insulating base member having pivot bearing seats at its outer face, a switch member, a pivot pin engaging said switch member and resting in said bearing, a shifter member 115 slidably engaging the inner face of the insulating base, a plunger for throwing the switch member and for engaging both said switch member and the shifter member, and a spring compressed and confined between a part of the plunger and the switch member thereby to hold both of said members to the base.

3. A socket of the class described including an insulating base having a central opening and pivot bearing seats formed at opposite sides of said opening in the outer face of the base, a switch member arranged in said central opening, a pivot pin engaging one end of the switch member and resting 125

- in said bearing seats, a shifter member slidably engaging the inner face of the base, a plunger engaging the shifter member and the switch member, a spring confined between the plunger and the switch member for holding both of said members to opposite faces of the base, and an insulation member secured to the outer face of the base and covering said pivot pin.
- 5 4. A socket of the class described including insulating cap and base members formed to provide a switch chamber and a guide-way, said base member having pivot bearing seats in its outer face, a screw shell contact carried by the base member, a line wire terminal carried by the base member and contacting with the screw shell, another line wire terminal carried by the base member, a switch contact connected with the last
- 10 named line wire terminal and arranged in 20 the switch chamber, a switch arranged in said switch chamber, a pivot pin engaging said switch and resting in the said bearing seats, a center plug contact carried by the base member, an insulation piece arranged 25 between said pivot pin lying in the bearing seats and the center plug contact, another switch contact engaging said center plug contact and having a portion lying within the switch chamber, a shifter member in said 30 guide-way and slidably engaging the inner face of the base and a spring pressed plunger confined between the shifter member and the switch to hold the latter and the shifter member to opposite faces of the base.
- 15 In testimony whereof I hereunto affix my signature.

EDGAR H. FREEMAN.
